UNITED STATES PATENT OFFICE.

DAVID SHERWOOD KENNEDY, OF BROOKLYN, NEW YORK, ASSIGNOR TO MERGEN-THALER LINOTYPE COMPANY, A CORPORATION OF NEW YORK.

TYPOGRAPHICAL MACHINE.

1,136,536.

Specification of Letters Patent. Patented Apr. 20, 1915.

Application filed August 14, 1914. Serial No. 856,762.

To all whom it may concern:

Be it known that I, DAVID SHERWOOD KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, and more particularly to linotype machines of the general organization represented in Letters Patent of the United States, No. 436,532, to O. Mergenthaler. In machines of this type it is the common practice to make use of matrices representing characters other than those controlled by the keyboard. These extra or "sorts" matrices are inserted by hand into the line in 20 the course of composition and are subsequently delivered to the distributer, from which ordinarily they descend through a receiving tube into a pi-stacker or receptacle at the front of the machine.

25 In machines wherein are employed a plurality of magazines, any one of which may be selected and brought into operation, the larger and more varied assortment of characters provided thereby is again supplemented by the employment of additional or sorts matrices, which correspond more or less in face or style to the face or style carried by the active magazine. For instance, in my U. S. Letters Patent, No. 1,064,487, 30 or in U. S. Letters Patent to N. Dodge, No. 1,078,612, is illustrated a plurality of receptacles or pi-stackers, one for each magazine, in combination with automatic means whereby one or another will be rendered active 35 according to the magazine selected, so that the sorts appertaining to each magazine will be received in a separate receptacle, and will be thus readily available to the compositor without the necessity of searching through 40 a mixed mass to discover the particular face or style desired.

45 It is a prominent feature of my present invention to provide means whereby the sorts matrices may be delivered to all of the receptacles or pi-stacking devices simultaneously. One of the principal advantages of this arrangement is that it becomes possible to mix sorts matrices of different fonts or styles and subsequently secure their auto-

matic delivery to the appropriate receptacles. This I preferably accomplish by the employment of a plurality of tubes or conductors leading from a common distributor to each of the sorts receptacles, and by forming the distributor with additional combinations adapted to coöperate with the respective combinations of the different sets of sorts.

55 In the accompanying drawings, I have shown my invention only in preferred form and by way of example, and as applied to two specific styles of machines, but many changes and variations may be made therein, and in its mode of application, which will still be comprised within its spirit. 60 Generally speaking, I desire it to be understood that I do not limit myself to any specific form or embodiment, except in so far as such limitations are specified in the claims.

75 Referring to the drawings: Figure 1 is a side elevation of a portion of a linotype machine, having my invention applied thereto; Fig. 2 is a rear view, partly broken away, of a part of the distributing mechanism, etc.; Fig. 3 illustrates the forms of sorts matrices adapted to coöperate therewith; Fig. 4 is a rear view, partly broken away, of a portion of another style of machine, with my improvements embodied 80 therein; and Fig. 5 illustrates the forms of sorts matrices adapted to coöperate therewith.

85 Referring to Figs. 1, 2 and 3, the different fonts of ordinary matrices are stored as usual in the several superposed magazines A, three of which are shown by way of illustration, and any one of which may be brought into operative relation to the single distributing apparatus. After the slug has 90 been cast, the matrices are delivered to the usual longitudinally grooved bar B, along which they are caused to travel by the screws B¹, and from which they drop in the usual way into their proper channels in the 95 magazine. The parts so far described, and their mode of operation, may be of any approved or desired character, and in themselves constitute no part of my present invention. The sorts matrices X¹, X², X³, are 100 preferably stored in the receptacles or stacking devices D¹, D², D³, respectively, and after their employment in the line are deliv-

ered to the same distributor bar. To permit their mixing and subsequent restoration to the proper receptacle, it will be noted that the matrices of each set are formed with the same tooth combination, Y^1 , Y^2 , Y^3 , respectively, and that the bar B, in addition to the ordinary combinations, is formed with additional combinations to correspond therewith. In the example shown (see Fig. 2), 10 the bar B is formed with the special combination B^1 to release the matrices X^1 into the tube or conductor C^1 , through which they pass to the receptacle D^1 ; and with the special combination B^2 to release the matrices X^2 into the tube or conductor C^2 , whereby they are returned to the receptacle D^2 ; and the end of the bar is so located that the matrices X^3 pass entirely along it and drop into the tube C^3 , whereby they are 20 stored to the receptacle D^3 . In this arrangement, the upper ends of the tubes are in close proximity to each other and the matrices pass into them from the bar at contiguous points.

25 In Figs. 4 and 5, a different style of machine is illustrated, equipped with a series of superposed magazines F, and at the side thereof an additional magazine G. In this instance also a single distributing bar E is 30 employed, but of extended length so as to deliver matrices to the operative one of the magazines F, and also to the further magazine G, all in the manner well understood in the art. In this mechanism, the 35 tubes or conductors C^4 and C^5 are not mounted in close proximity, but at a considerable distance from each other, the former being located between the magazines F and the magazine G, and the latter be- 40 yond the magazine G. Correspondingly, the bar E is formed with the special combination E^4 located above the conductor C^4 so as to deliver the sorts matrices X^4 into it, and terminates just short of the conductor 45 C^5 so that the sorts matrices X^5 will drop off the end of the bar into the said conductor. The matrices X^4 and X^5 with their corresponding toothed combinations Y^4 and Y^5 are shown in Fig. 5. It will be seen that 50 the general principle involved, namely the simultaneous delivery of different kinds of sorts matrices to their appropriate receptacles from different points of the same distributing apparatus, is the same in both 55 styles of mechanism, and that the several modes of application simply illustrate the adaptability of the invention to various conditions.

60 It will be observed that in combining the different sets of matrices, ordinary and sorts, the former are provided in the usual manner with distributing combinations according to character, and each set of the latter with the same combination irrespec- 65 tive of character; and that the distributor

bar is correspondingly provided with a series of combinations to coöperate with those of the ordinary matrices, and with additional combinations to coöperate with those of the sorts matrices, the number of such 70 additional combinations being the same as the number of sets of sorts matrices. In other words, the distributor delivers some matrices at different points according to character and others at other points irre- 75 spective of character. In this way, it is possible to distribute the sorts matrices into a plurality of receptacles or pi-stackers at the same time, so that matrices from any one or all of the receptacles may be set in 80 line with matrices from any one of the magazines, thus permitting matrices of various kinds, sizes or fonts to be composed in the same line for producing matter of many different descriptions.

85 As previously stated, I have shown my invention only in preferred form and by way of example, and as adapted in particular embodiments. However, many other modifications and alterations therein, and in its mode of application, will suggest themselves to those skilled in the art, without departure from its scope.

Having thus described my invention, its construction and mode of operation, what I 95 claim and desire to secure by Letters Patent of the United States, is as follows:

1. In a typographical machine, the combination of a channeled magazine to contain a regular font of matrices, a distributor to deliver the matrices into one or another of the channels according to character, a plurality of receptacles wherein the sorts matrices are arranged irrespective of character and in an exposed condition to permit 100 their ready withdrawal by hand, and means whereby the sorts matrices may be delivered from the distributor to all of said receptacles simultaneously.

2. In a typographical machine, the combination of a channeled magazine, a distributor to deliver the matrices thereto, a plurality of receptacles wherein the sorts matrices are arranged, irrespective of character, and in an exposed condition to permit 105 their ready withdrawal by hand, and a corresponding plurality of tubes or conductors leading from the distributor to the respective receptacles.

3. In a typographical machine, the combination of a plurality of magazines, a distributor common to all of said magazines, a plurality of sorts receptacles, one for each magazine, and means whereby the sorts matrices may be delivered from the distributor 115 to all of said receptacles simultaneously.

4. In a typographical machine, the combination of a plurality of magazines, a distributor common to all of said magazines, a plurality of sorts receptacles, one for each 120

magazine, and a corresponding plurality of tubes or conductors leading from the distributor to the respective receptacles.

5. In a typographical machine, the combination of a channeled magazine, a distributor having a series of distributing combinations, one for each channel of the magazine, a plurality of sorts receptacles, and a corresponding plurality of tubes or conductors leading from the distributor to the respective receptacles, the distributor hav-

ing an additional distributing combination to deliver the sorts matrices into one of said tubes, and being arranged so as to allow other sorts matrices to drop from the end 15 thereof into another of said tubes.

In testimony whereof, I have affixed my signature in presence of two witnesses.

DAVID SHERWOOD KENNEDY.
